UNITED STATES PATENT OFFICE.

ELIHU THOMSON, OF SWAMPSCOTT, MASSACHUSETTS.

GAS-ENGINE.

SPECIFICATION forming part of Letters Patent No. 669,737, dated March 12, 1901.

Application filed February 23, 1898. Serial No. 671,240. (No model.)

To all whom it may concern:

Be it known that I, ELIHU THOMSON, a citizen of the United States, residing in the town of Swampscott, county of Essex, and State of Massachusetts, have invented a new and useful Improvement in Gas-Engines, of which the following is a specification.

The present invention has for its object the simplifying of working of certain types of engines suitable for the use of combustible gas or hydrocarbon vapor, such as vapor of oil or gasoline.

The invention applies to that type of engine in which the cycle of operations is similar to the Otto cycle in that a charge is indrawn on the first outward stroke, which is compressed on the first return stroke, the third or second outward stroke being the power-stroke and the fourth the return or exhaust stroke. In my invention, however, the charge of combustible is not drawn in or mixed with the charge of air during the intake-stroke, as above mentioned; but the charge of combustible is automatically delivered during the power-stroke to the body of compressed air, which has been brought to a high pressure on the compression-stroke. The time of this delivery may by a part of my invention be governed or controlled. In this way of working there is no combustible charge compressed.

Briefly the cycle as modified in my invention is as follows: First the forward motion of the piston or intake-stroke takes place at the same time that an inlet-valve is opened and admits air to fill the cylinder. During this stroke or at its completion a combustible charge of oil, gasoline, or other combustible is pumped into a small chamber in communication with the main cylinder by means of suitable passages, to be described. The introduction therefore of the combustible charge does not require to be made against any pressure or head, and it does not mix with the entering charge of air, but is sent into a small receptacle, where it remains during the whole of the compression-stroke. The compression-stroke is made by the return of the piston, and the closure of the inlet-valve prevents the escape of the air, which is held in a space continually diminishing as the piston moves backward. Meanwhile, however, through suitable passages a portion of the compressed-air

charge passes into the receptacle or chamber; into which the fuel gas or vapor has already been pumped. The completion of the compression-stroke is made at such a high pressure that the air, assisted by the heat of the cylinder-walls, will be at a sufficiently high temperature to cause combustion when there is any combustible mixed with it. This pressure may be, according to the size of the engine, from three hundred to five hundred pounds to the square inch, more or less. In the next or power stroke the return of the piston expands the highly-compressed hot gas, and at the same instant the fuel charge, being driven by the portion of highly-compressed gas which has been forced into the receptacle containing it, passes out into the main cylinder and burns, thus adding to the volume of charge, but not increasing its pressure to any considerable extent. The combustion is then made during the power-stroke, the piston is driven forward, and finally on its return with an exhaust-valve open the waste gases are discharged ready to begin the cycle over again.

Another feature of my invention is the timing of the entrance of the combustible charge into the cylinder. This I do by causing a sudden marked drop of the compression-pressure at the instant desired, as just at the conclusion of the compression-stroke. When the charge of air is compressed to the highest point, a small valve may be opened to allow a certain portion of this charge to escape, as into a separate receptacle or chamber, and thus cause a sudden drop of pressure, the instant effect of which is to give rise to an expulsion of the combustible charge and the mingling thereafter with the highly compressed and heated air, after which the power-stroke is finished in the ordinary manner.

I have illustrated my invention by embodying it in an engine shown in the drawings; but it must be understood that the invention is not specifically to the particular form of gas-engine there shown, but to the means employed in its operation in accordance with the cycle above stated and the method by which the operation is accomplished. I do not lay stress upon the details of mechanical construction, as they may be varied very

widely, and they are introduced here to illustrate the general action or the principle involved. Some of them, however, being valuable in connection with the engine of my invention 5 are claimed in connection with the present case.

Figure 1 is a side elevation, partly in section, of an engine involving the present invention. Fig. 2 is a plan, part of which is 10 in section through the line X X, Fig. 1. Fig. 3 is simply an enlargement of the valves and working parts in the cylinder-head of Fig. 1, made so as to be more clearly displayed. Fig. 4 is a modification of the details.

15 Any suitable crank or crank-shaft, as at K, is provided, furnished with a driving-wheel W, supported on suitable bearings. A connecting-rod R unites the crank-pin with the moving piston P within the cylinder C in 20 the ordinary way. This cylinder may be water-jacketed, if desired, to avoid undue heating. A cylinder-head is shown, and at I an inlet-valve opening and closing communication between the cylinder-space and the external air. There is also the valve E, opening and closing communication with the exhaust-pipe E². The small valve E (shown 25 above the exhaust-valve) may be called the "timing - valve." These parts are more 30 clearly seen in Fig. 3, to which reference may be had for better understanding. There is a little space or receptacle F back of the cylinder-space, which communicates with the said cylinder through a passage or passages. 35 It also communicates with a feed-pump for combustible, which is indicated at O and which serves when operated to inject through suitable valves a fuel charge into the space or receptacle F. This space or receptacle 40 communicates by passages, as at Q and J, with the cylinder. The passage Q is governed by a valve-opening only, however, in case of any difference of pressure during the compression between the gases in the cylinder C and those in F. It tends, therefore, to 45 equalize the pressures in F and C. It might be dispensed with, but is desirable where high-speed work is to be accomplished. It does not, however, permit free equalization of 50 pressures between receptacles F and C in the reverse way—i. e., from F to C—but closes in that direction, so that whatever enters during the compression into receptacle F by way of either the jet-passage J or the valve-covering 55 passage Q must all return by the passage J. The passage J constitutes, in effect, an atomizer or mixing-jet, whereby whatever materials are found unmixed or separate in receptacle F must become thoroughly stirred together 60 or mixed in passing from F to space C of the cylinder. Thus if F be divided by a wall, so as to have a space G distinct from the space H and with communication with the opening J only through fine passages and a quantity 65 of oil has been sent into the receptacle F and exists in G, then on a sudden fall of pressure in the cylinder C there is an outrush of the

compressed gas from H to J and an outrush of the oil or oil-vapor from G to J, where they are mixed and drawn violently into the cylinder-space. As a means for regulating the action of this, which may be called the "atomizing" or "mixing" jet J, I have shown an adjustable commingling-valve, controlled by head N, which tends when screwed backward 70 or forward to adjust the size or relation between the passages from G and H, respectively, so as to prevent a too sudden rejection of the combustible charge G on the second outward or power stroke of the piston P.

80 Similar parts, in so far as they are shown in Fig. 2, are lettered as in Figs. 1 and 3. It will be seen that the small valve V, if opened, would connect the cylinder-space with the exhaust passage or pipe. This is one way of arranging the time of drop-pressure by valve V. In Fig. 4, however, this valve opens communication from cylinder-space C into a special receptacle D, so that the gas which is thus 85 allowed to escape from the cylinder C and cause a drop of pressure is held in D for subsequent return and expansion during the power-stroke, valve V being kept open during that stroke only.

90 For the proper working of the valves in their sequence, demanded by the cycle above stated, suitable cams may be mounted upon a cam-shaft L, which cam-shaft is driven in definite relation to the motions of the crank K—that is, a gearing is provided which keeps the cam-shaft L in definite working relation to the main shaft. In general this gearing reduces the speed of the cam-shaft L to one-half the usual speed, as is customary in gas-engines. This shaft may also carry a governor M for controlling the speed by causing the admission-cams for combustible or the pump O to miss its stroke or diminish the amount of its action in throwing in combustible. This, however, is easily accomplished 100 in many different ways and is not an essential feature of the present invention and is here simply described to make clear the operations. The cam which governs valve I opens valve I during the forward motion of the piston or the intake-stroke, allowing air to fill the cylinder. During this stroke or near its conclusion the cam on the cam-shaft L, which operates the pump O, feeding combustible, which cam is marked a in Fig. 1 and works 105 upon lever l, operates the pump and forces a charge of combustible into receptacle F just before the compression-stroke is effected. This pumping of combustible is, however, governed by the governor M, which, if the speed be too high, raises one end of the small lever b and disengages by small lever d the lever l from the pump-piston, the return of which is effected by a spring after any stroke. The compression-stroke begins with all the 110 valves shut, and during the stroke the valve governing passage Q may be forced open by the rush of gas under compression tending to reach receptacle F on account of the pas-

sages through J being too small or restricted. The compression-stroke being carried on, a high pressure is obtained sufficient to heat the compressed air in the cylinder sufficiently 5 to cause the combustion of any combustible sent thereinto, and this stroke is followed by the outward motion of the piston, at which time the valve Q closes and the discharge from the receptacle F begins. This discharge mixes or atomizes the fuel passing out through the opening J into the cylinder, and combustion takes place within the cylinder-space during the power-stroke. This action might be a little late, owing to the 15 fact that not until the piston begins to leave its farthest inward position and not until the crank has therefore passed well over the dead-center does the jet J deliver fuel. To accelerate this delivery, a suitable cam e operates the small valve V to relieve the pressure in C slightly at or about the time the crank is on dead-center and space within the cylinder C has reached its smallest volume. This provokes the discharge from the receptacle 25 F, and, as stated before, the escape or lowering of pressure from valve V may be temporary by providing a restricted chamber D, into which the excess escapes. If the cam e be made so as to keep the valve V open during 30 the power-stroke, the stored pressure in chamber D, Fig. 4, will add its expansion effects to those of the gas within the cylinder C itself, and the chamber D will be ready after the closure of valve V for the renewal 35 of the actions. If the connection of valve V opens into the outside air or inside pipe E², as in Fig. 1, the opening thereof is but momentary, followed by immediate closure, so as not to allow much fall in pressure at C, 40 which would mean a loss of effectiveness. During the power-stroke or second forward motion of the piston P the compressed gas in receptacle F discharges itself almost completely, and the exhaust-valve E is then 45 opened by a suitable cam f while the return or exhaust stroke is effected, which drives out the products of combustion and waste

gases ready for the beginning of the same set of operations.

I am aware that it is not new to draw in a 50 charge of air, compress the same, and then inject by suitable pumps a quantity of fuel, gas, or vapor, which burns during the power-stroke; but in my invention the injection of the fuel takes place at a time when there is 55 no back pressure opposing its forward movement, and the actions occurring in the cylinder during compression are made the means for the discharge of fuel into the cylinder after compression without the aid of external injecting appliances worked from the outside, and thus I am enabled to obtain, with great 60 simplicity of parts, effects which have hitherto been unattainable.

What I claim as new, and desire to secure 65 by Letters Patent of the United States, is—

1. In an internal-combustion engine of the kind described, a cylinder for receiving a compressed-air charge, as produced by the motion of its piston after the intake, a cylinder-head having within it a chamber for the reception of a charge of oil fuel and a portion of the compressed-air charge from the cylinder, said chamber being provided with a valve opening toward it from the cylinder-space; in 70 combination with an atomizing-jet, the openings to which are at the bottom of said receptacle, substantially as described.

2. In an internal-combustion engine, having a cylinder and a piston traversing the 80 cylinder-space, the cylinder-head or a portion of the cylinder-wall having combined with it an atomizing-jet and a fuel-receptacle as described, and an inlet-valve from the cylinder-space to the receptacle, with means such 85 as a pump for pumping oil into the receptacle when little or no pressure exists therein, substantially as described.

In witness whereof I have hereunder set my hand this 21st day of February, 1898.
